CLEANING AND EXTRACTING MACHINE

Alfred Hjelm, Plentywood, Mont., assignor of one-half to Andrew Hansen, Wolf Point, Mont.

Application June 1, 1937, Serial No. 145,709

14 Claims. (Cl. 68—25)

This invention relates to cleaning and drying apparatus and particularly to the type designed for use in the cleaning of clothes and other fabric articles with the use of gasoline or other liquid 5 solutions, and the primary object is to provide a device that is not only very efficient and practical, but which is also extremely simple in design and construction with a result that it can be manufactured at a cost that will justify its use 10 for home or domestic purposes. More specifically the device comprises a very simple supporting frame in which is tiltably mounted a rotary container that is so designed that it will be operative to perform both cleaning and extracting operations, according to its tilted position, and may 15 extract the liquid without discharging it from the container even though the container and all its parts are substantially united in a single composite structure or unit. Further and more detailed objects will be disclosed in the course of 20 the following specification, reference being had to the accompanying drawings, wherein:

Fig. 1 is a side elevation of the machine showing the receptacle and receptacle frame in the angularly tilted position as used for cleaning 25 purposes.

Fig. 2 is a top or plan view of the machine with the receptacle in the vertical or extracting position.

Fig. 3 is a front elevation of the machine with the cleaning and drying receptacle shown in 30 diametrical section.

Fig. 4 is a detail plan view of the outer or arcuate closure plate employed at the upper end 35 of the receptacle.

Fig. 5 is an enlarged sectional view on line 5—5 in Fig. 3.

Fig. 6 is an enlarged section on line 6—6 in Fig. 3.

Referring to the drawings more particularly and by reference characters, 7 designates a rectangular base, preferably formed of angle iron bars, and is provided with suction cups 8 for engagement with the floor to increase the stability 40 of the machine when in use. The base frame also includes a pair of laterally arranged vertical standards 9, attached to the base and braced with respect thereto by brace bars 10.

At their upper ends the standards 9 are provided 50 with aligned bolts 11 which serve as pivot supports for a rectangular receptacle supporting frame 12. When the frame 12 is in vertical position its lower end portions have bracing contact with adjacent inner faces of the standards 9, and the receptacle frame may be releasably locked

in this position by a keeper 13 mounted on one of the standards and having a finger 14 movable through the standard and for engagement with a perforation 15 in the adjacent bar of frame 12. The keeper is actuated by a spring 16 but may be easily moved outwardly to withdraw the lock finger when the frame 12 is to be tilted into or out of its vertical position.

The frames are further connected by a link 17, to limit the tilting movement of the receptacle frame, and this link is preferably though not necessarily pivoted at 18 to frame 12, while its other end has a headed stud 19 movable in a slot 20 in adjacent standard 9. This slot may have an offset notch at its upper end (see Fig. 1) 15 wherein the stud may rest to releasably hold the frame 12 in tilted position.

The frame 12 includes a lower cross bar 21 and two spaced, upper cross bars 22 and 23, which cross bars serve as bearing supports for lower 20 and upper stud shafts 24 and 25, respectively, of the receptacle 26, and which shafts are rigidly fixed to the ends of the receptacle, axially thereof, to rotate therewith. The shaft 25 is provided, intermediate bars 22 and 23, with a small pulley 25 27, connected by a belt 28 to a larger pulley 29 on a shaft 30, also journaled for rotation in the bars 22 and 23. A hand crank 31 has a non-circular socket adapted to fit either of shafts 25 or 30 and may be shifted from one to the other depending upon the receptacle rotation speed desired. In ordinary cleaning operation, when relatively low speed is desired, the crank is applied to shaft 25 to apply the direct and relatively stronger force needed to operate the receptacle 35 in its inclined position. When the machine is to be used for extraction purposes, however, the receptacle is restored to vertical position, as in Figs. 2 and 3, and the crank is applied to shaft 30. Under this condition there is considerable 40 less resistance to rotation, which in turn permits of the higher speed drive effected by the different diameter of pulleys.

The receptacle 26 is trunco-conical in form and defines a general cleaning chamber 32 and a 45 base or liquid chamber 33 (Fig. 3) having a capped liquid discharge opening 34. At its upper end the receptacle has a top 35 with an opening closed by a friction cover 36, and through which opening the clothes or other articles to be 50 treated are inserted and removed. The upper end of the receptacle 26 proper is provided with a rigid hood or tapered shell 37, forming a head space or chamber above the cover 35. This hood is operative to rigidly connect the receptacle to 55

the supporting and driving shaft 25, and has a lateral opening or passage which is normally closed by an arcuate, circularly adjustable door 38. This door has frictional sliding contact 5 against the inner surface of hood 37 and is provided with an upper, radial wing 39 pivotally engaging a stud 40 at the lower end of shaft 25. In its lower end portion the receptacle 26 is provided with a cylindrical container 41, the 10 upper edge of which is in contact with and welded or otherwise suitably fastened to the receptacle wall, as at 42 (see Fig. 3) while the lower end of the container is annularly spaced with respect to the adjacent and relatively wider receptacle 15 wall portion at that level. The container wall is profusely perforated, as at 43, but the container bottom, 44, is imperforate so that liquid cannot pass through it. The bottom of the container is provided, immediately outside the container wall, 20 with an annular flange 45, which is also imperforate. This flange is flared outwardly and upwardly, but not sufficiently to reach or touch the receptacle wall. In fact it is important that the parts be so proportioned that a well defined 25 but narrow annular space 46 be left between the upper edge of the flange and the outer receptacle, as will presently be set forth. The container 41 is further provided with agitator blades 47 which serve the double function of assisting in the 30 cleaning operation, by more effective tumbling of the articles being cleaned, and also serve to reinforce the container parts 41 and 44 with respect to each other.

The operation of the machine may be described as follows:

Before any material is placed in the receptacle 26 it is preferably first secured in its vertical position, as shown in Figs. 2 and 3, at which time the device 13 is operative to releasably 40 fasten the receptacle frame 12 with respect to the standards 9. With the device in this position the door 38 is opened, and the cover 36 is removed to permit placing of articles and cleansing fluid in the receptacle. The amount of fluid should be 45 equal to the cubic capacity of the chamber 33 below the container bottom 44, and extending not higher than the upper edge of the flange 45. With this, or a lesser amount of fluid inserted, and with the clothes or other fabric articles to be 50 cleaned also placed in the receptacle, the cover 36 is replaced and the door 38 is reclosed.

The latch 13 is now released so that the receptacle and receptacle frame can be tilted to the position shown in Fig. 1, in which position the unit is releasably secured by the link 17. With the receptacle in this position the level of the fluid in the lower corner portion thereof will be such as to extend considerably above the flange 45 and completely saturate the articles 60 within the container 41.

The crank 31, or other power element, is then applied to the shaft 25, to rotate the receptacle 26. This rotation, particularly under the action of the agitators 47, causes the articles to be 65 cleaned to be intermittently tumbled into and lifted from the fluid body, and this action or movement will quickly and efficiently effect the desired cleaning operation on the articles under treatment.

70 When the cleaning operation has been completed, the frame 12 is restored to its vertical position and the crank 31 is then applied to the shaft 30, as shown in Figs. 2 and 3. Turning of the crank now drives the receptacle 26 at a much 75 greater speed because of the difference in the

sizes of the two pulleys 27 and 29. The rapid rotation of the receptacle and the clothes or other articles contained therein will set up a centrifugal action that will force the liquid radially outward through the perforations 43. As this occurs the major portion of such liquid will be thrown against the inner wall of the receptacle 26 proper, and as this wall is tapered and flares outwardly as it extends downward from point 42, the liquid thus engaging this surface will be impelled downwardly through the annular passageway 46 and into the chamber 33. The liquid escaping through the lowermost perforations 43 will strike the upwardly flared flange 45, with a result that it will be deflected upwardly and over 15 the edge of the flange, to thus be discharged against the inner wall surface of the outer receptacle; and will thereafter also pass downwardly through the passage 46 and into the chamber 33. The extracting operation may be 20 continued until the cleaned articles have been entirely dried, or it may be continued only sufficiently to extract the major portion of the moisture, after which the articles may be subjected to further drying after being removed 25 from the receptacle. It will thus be seen that the flange 45 in no way obstructs the extracting operation, but on the other hand permits a relatively higher level of cleansing fluid within the chamber 33 without letting such fluid run back 30 into the container 41.

It is understood that suitable modifications may be made in the structure as disclosed, provided such modifications come within the spirit and scope of the appended claims. Having now 35 therefore fully illustrated and described my invention, what I claim to be new and desire to protect by Letters Patent is:

1. In a cleaning and extracting machine, a supporting frame, a liquid holding receptacle mounted for rotation in the frame and adjustable whereby it may be operated with its axis of rotation disposed in either vertical or inclined positions, and a container in the lower portion of the receptacle but spaced from the bottom thereof to support and tumble articles to be cleaned, said container having perforated side walls and fixed to the receptacle for rotation therewith but spaced therefrom at their lower portions.

2. In a cleaning and extracting machine, a liquid holding receptacle mounted for rotation at relatively high and low speeds and tiltably adjustable so that it may be rotated with its rotating axis disposed in selective relatively angular positions, and means fixed to and rotatable with the receptacle for supporting articles to be cleaned in the receptacle but above the bottom end thereof, the said supporting means including perforate side walls secured at their upper portions within the receptacle and spaced at their lower portions therefrom.

3. In a cleaning and extracting machine, a supporting frame, a liquid holding receptacle mounted for rotation in the frame and adjustable whereby it may be operated with its axis of rotation disposed in either vertical or inclined positions, and a container in the lower portion of the receptacle but spaced from the bottom thereof to support and tumble articles to be cleaned, said container having perforated side walls and fixed to but spaced from the receptacle for rotation therewith, said receptacle being circumferentially enlarged at its lower extremity to form a liquid chamber below the container of greater diameter than the receptacle portion thereabove.

4. In a cleaning and extracting machine, a main frame, a second frame tiltably supported in the main frame and for adjustment into vertical and inclined positions, a receptacle rotatably mounted in the second frame and for containing cleaning liquid and the articles to be cleaned, and means secured in spaced relation within and rotatable with the receptacle for supporting the articles to be cleaned in spaced position above the bottom end of the receptacle. 5
5. In a cleaning and extracting machine, a generally trunco-conical receptacle mounted for rotation about its axial center and tiltably into vertical and inclined positions, a container secured in the receptacle for rotation therewith but with its bottom spaced from the bottom end of the receptacle and its annular wall secured at its upper portion within the adjacent wall portion of the receptacle. 10
10. 6. In a cleaning and extracting machine, a generally trunco-conical receptacle mounted for rotation about its axial center and tiltably into vertical and inclined positions, a container secured in the receptacle for rotation therewith but with its bottom spaced from the bottom end of the receptacle and its annular wall secured at its upper margin to and spaced within the adjacent wall portion of the receptacle, and means for rotating the receptacle. 20
20. 7. In a cleaning and extracting machine, a generally trunco-conical receptacle mounted for rotation about its axial center and tiltably into vertical and inclined positions, a container secured in the receptacle for rotation therewith but with its bottom spaced from the bottom end of the receptacle and its annular wall spaced within the adjacent wall portion of the receptacle, and means for rotating the receptacle, said container having a perforate side wall and imperforate bottom, and the said side wall being secured at its upper portion to the receptacle. 30
30. 8. In a cleaning and extracting machine, a generally trunco-conical receptacle mounted for rotation about its axial center and tiltably into vertical and inclined positions, a container secured in the receptacle for rotation therewith but with its bottom spaced from the bottom end of the receptacle and its annular wall spaced at its lower portion within the adjacent wall portion of the receptacle, the said wall being perforated, said container having an imperforate bottom and an annular bottom flange projecting upwardly into the space between said adjacent receptacle and container walls. 40
40. 9. In a cleaning and extracting machine, a generally trunco-conical receptacle mounted for rotation about its axial center and tiltably into vertical and inclined positions, a container secured in the receptacle for rotation therewith, but with its bottom spaced from the bottom end of the receptacle and its annular wall spaced at its lower portion within the adjacent wall portion of the receptacle, the said wall being perforated, and agitator members extending into the container. 50
50. 10. In a cleaning and extracting machine, a receptacle mounted for rotation about a vertical axis and tiltably adjustable for rotation about an inclined axis, a container secured within the receptacle for rotation therewith, the said container having a perforated wall, the receptacle wall adjacent the container flaring outwardly and downwardly, said container having an imperforate bottom and a flange thereabout flaring upwardly toward but spaced from the said receptacle wall to form an annular passage therebetween for the escape of liquid into the bottom portion of the receptacle during the extracting operation. 10
10. 11. In a cleaning and extracting machine, a receptacle mounted for rotation about a vertical axis and tiltably adjustable for rotation about an inclined axis, a container secured within the receptacle for rotation therewith, the receptacle wall adjacent the container flaring outwardly and downwardly, said container having an imperforate bottom and a flange thereabout flaring upwardly toward but spaced from the said receptacle wall to form an annular passage therebetween for the escape of liquid into the bottom portion of the receptacle during the extracting operation, the container wall being provided with openings to permit centrifugal separation of liquid from cleaned articles supported in the container. 15
15. 12. In a cleaning and extracting machine, a receptacle mounted for rotation about a vertical axis and tiltably adjustable for rotation about an inclined axis, a container secured within the receptacle for rotation therewith, the receptacle wall adjacent the container flaring outwardly and downwardly, said container having an imperforate bottom and a flange thereabout flaring upwardly toward but spaced from the said receptacle wall to form an annular passage therebetween for the escape of liquid into the bottom portion of the receptacle during the extracting operation, the said container wall being perforated, and agitators in the container to facilitate tumbling of articles therein during the cleaning action when the receptacle and container are rotated about the inclined axis. 20
20. 13. In a cleaning and extracting machine, a receptacle and a container having a perforate side wall and imperforate bottom, the upper margin of the side wall being secured in contact with the inner surface of the receptacle but the lower portion of the side wall being spaced from the said inner surface of the receptacle. 25
25. 14. In a cleaning and extracting machine, a rotatable and tiltable receptacle, a container mounted within the receptacle, the said container having a perforate side wall secured at its upper margin within the receptacle, the lower portion of the container being spaced from both the sides and bottom of the receptacle, the said container having an imperforate bottom, and a flange turned upwardly about the bottom of the container between the side walls of the container and receptacle. 35
35. 15. ALFRED HJELM. 60
